(57) **CLAIM**

The ornamental design for a sheet for laundry use, as shown and described.

DESCRIPTION

FIG. 1 is a top perspective view of a first embodiment of a sheet for laundry use showing my new design;

FIG. 2 is a bottom perspective view thereof;

FIG. 3 is a top plan view thereof;

FIG. 4 is a bottom plan view thereof;

FIG. 5 is a front view thereof;

FIG. 6 is a back view thereof;

FIG. 7 is a right-side view thereof;

FIG. 8 is a left-side view thereof;

FIG. 9 is another top view thereof;

FIG. 10 is a top perspective view of a second embodiment of the sheet for laundry use showing my new design;

FIG. 11 is a bottom perspective view thereof;

FIG. 12 is a top plan view thereof;

FIG. 13 is a bottom plan view thereof;

FIG. 14 is a front view thereof;

FIG. 15 is a back view thereof;

FIG. 16 is a right-side view thereof;

FIG. 17 is a left-side view thereof;

FIG. 18 is another top view thereof;

FIG. 19 is a top perspective view of a third embodiment of the sheet for laundry use showing my new design;

FIG. 20 is a bottom perspective view thereof;

FIG. 21 is a top plan view thereof;

FIG. 22 is a bottom plan view thereof;

FIG. 23 is a front view thereof;

FIG. 24 is a back view thereof;

FIG. 25 is a right-side view thereof;

FIG. 26 is a left-side view thereof;

FIG. 27 is another top view thereof;

FIG. 28 is a top perspective view of a fourth embodiment of the sheet for laundry use showing my new design;

FIG. 29 is a bottom perspective view thereof;

FIG. 30 is a top plan view thereof;

FIG. 31 is a bottom plan view thereof;

FIG. 32 is a front view thereof;

FIG. 33 is a back view thereof;

FIG. 34 is a right-side view thereof;

(Continued)

FIG. 35 is a left-side view thereof; and,
 FIG. 36 is another top view thereof.
 The broken lines shown in the FIGS. 9, 18, 27 and 36 are for
 the purpose of illustrating environmental structure and form
 no part of the claimed design.

1 Claim, 24 Drawing Sheets
